PARACHUTE PACK STIFFENING MEANS

Spencer W. Severance and Joseph J. Rutkowski,
Trenton, N. J., assignors, by mesne assignments,
to Switlik Parachute Company, Inc.,
Trenton, N. J., a corporation of New Jersey

Application March 8, 1946, Serial No. 652,935

3 Claims. (Cl. 244—148)

1

This invention relates to parachutes.

An object of the invention resides in the provision of a back pack which is so constructed that it will possess the advantages of a soft pack without the disadvantages and will at the same time possess the advantages of a stiffened pack without the disadvantages.

It is another object of the invention to so construct the pack that its form will be maintained by stiffening means and yet it will present a cushion like portion to the wearer's back in contradistinction to the rigid character of the back engaging portion of packs currently in use.

A further object of the invention resides in the provision of a pack that possesses the above advantages and which, while it fits the curvature of the body of the user, will permit him freedom of movement without interference.

Another object of the invention resides in so constructing the pack that, while there will be presented to the back of the user a cushion like portion, the contents of the pack, particularly the canopy, will be maintained in its original packed condition and will be prevented from shifting toward the bottom of the pack.

More specifically it is an object of the invention to provide a pack which is provided with a stiffening frame which is included in the pack but removed from the back engaging portion and which is provided with pockets for the canopy to maintain them in their original packed condition and against shifting.

Even more specifically it is an object of this invention to provide means which will maintain the pack in its packed form and yet will permit freedom of movement by the user, and which will maintain the elastic flap opening lines against displacement.

With these and other objects in view, which will appear as the description of the invention progresses, the invention includes the combination and arrangement of elements described in the specification, illustrated in the drawings and recited in the claims.

As the invention is admirably adapted for incorporation in a back pack it will be so described.

In the drawings:

Figure 1 is an elevation of a pack constructed in accordance with the invention;

Figure 2 is an edge or side elevation of the pack;

Figure 3 is a longitudinal section on line 3—3 of Figure 1;

Figure 4 is a transverse section on line 4—4 of Figure 1;

2

Figure 5 is a longitudinal section on line 5—5 of Figure 2;

Figure 6 is an elevation of one form of stiffening frame;

* Figure 7 is an elevation of one modified form of stiffening frame;

Figure 8 is an elevation of another modified form of the stiffening frame; and

Figure 9 is a detail perspective view.

Referring now to the drawings the cover of the pack includes a back or body engaging portion 1, to which are attached top and bottom flaps 2 and 3 and side flaps 4 and 5 which latter overlie the end flaps and one of which overlaps the other. These side flaps 4 and 5 are secured together by the usual cone fasteners 6 and rip cord 8, and they are also provided with the usual opening elastic cords such as 9 and 10 which extend around the pack and are at their ends secured to the flaps as shown in Figures 1 and 2 of the drawing. These elastic cords are, however, associated with the pack in a special manner as will be pointed out.

The back 1 of the pack is provided with transverse grooves, the number of which may vary but which are indicated in the drawing as two, 11 and 12, the provision of the grooves also resulting in partitions 13 and 14 to form pockets 15, 16 and 17 for receipt of the canopy 18 and the suspension lines 19 which lead to the risers 20 of the harness. These partitions may be of the desired distances apart. It has been found, however, that to locate the partition 14 at about or slightly below the waist line of the user and to locate the partition 13 at or about the shoulder blades results in a convenient, comfortable and advantageous articulation of the pack.

While of course the back 1 of the pack in the form described may be constructed by several methods, it has been found advantageous to construct it by forming what shall be termed gussets 21, such as illustrated in Figure 9 of the drawings. Each gusset is preferably, but not necessarily, U-shaped in cross section and is curved inwardly as at 22 to conform to the shape of the back of the user, which inwardly curved portion results in extended portion 23 which will lie at the side of the back of the user. The sections 24, 25 and 26 of the back portion of the pack cover are secured to the edges of the gussets as by stitching for example, and thus cause the back portion to take the transverse form of the back of the user, providing at the same time longitudinal pockets 27 which intersect the pockets 16, 17 and 18, and are for the reception of the adjacent

portions of the canopy and the bight portions of the folded suspension lines, as shown in the drawings.

When the edges 22 of the gussets are made straight instead of curved, as illustrated, the back engaging portion of the pack will be flat instead of curved which, of course, will merge the longitudinal pockets with the transverse pockets to a greater extent than when the gusset edges are curved.

This pack is provided with a stiffening frame which, however, will permit the pack to bend or articulate with the movements of the user.

In Figure 6 of the drawings the frame includes side bars 28, a bottom section 29 and upper and lower cross bars 30 and 31 respectively, the top and bottom cross bars being secured to or made integral with the side bars, the lower or bottom section 29 being hinged at 32 to the lower cross bar 31. In this case the lower section 29 is preferably made in one piece of integral or connected material. An upper section 33, which is constituted, preferably, by two pieces of material, is hinged at 34 to the upper cross bar 30.

The above referred to elements of the frame lie substantially in a plane and are made, preferably, of resilient material such as wire.

When incorporated in the pack the top and bottom sections 33 and 29 respectively lie within the pack as do also the side bars 28 as illustrated in Figure 3 of the drawings, while the cross bars 30 and 31 lie in the grooves 11 and 12, there being notches 35 provided at the ends of the gussets to accommodate the connection of the cross bars to the side bars of the frame.

It will be noted that the elastic cords 9 and 10 are located in the grooves at the back of the pack and pass over the sides of the frame to their points of securement to the flaps 4 and 5.

In the form of frame shown in Figure 7 of the drawings, the construction of the frame is substantially the same as that described in connection with Figure 6, except that the lower or bottom section 29' is made up of two elements hinged at 32' to the cross bar 31, there being the side bars 28 and the upper section 33 hinged to the upper or top cross bar 30 as in Figure 6.

In the form of frame shown in Figure 8 there are the cross bars 30 and 31, side bars 28 which, however, are made up of separate elements as shown rigid with the cross bars. This form also includes an upper section 33' which is made up of separate elements rigid with the upper cross bar 30, and a lower or bottom section 29'' which likewise is constituted by separate elements rigid with the lower or bottom cross bar 31.

The cross bars in these various forms are located in the pack, as described in connection with Figure 6, as are also the side bars and upper and lower sections.

All forms of the frame may, of course, and preferably are, formed of resilient material such as wire.

In the various forms the sides of the frame are bowed inwardly as illustrated to insure the conformation of the sides of the pack to the hip line so that the sides of the pack will not project materially. Thus the possibility of the sides of the pack becoming engaged with extraneous objects, during use, will be greatly reduced.

Moreover, in the various forms the cross members 31 and 32 will be slightly bowed inwardly toward the back of the user so that when they are flexed by the bending of the back of the user they will, because of the resiliency of the mem-

bers, return to their initial position to preserve the form of the pack.

In the forms shown in Figures 6 and 7 the upper ends of the members 33 are bent forwardly toward the shoulders of the user so that when the back is bent the upper end of the pack will follow and have no objectionable projections at the shoulder.

When the canopy and suspension lines are packed the flaps are thrown open, the elastic cords having been released, thus exposing the inside of the back of the pack to the packer.

The suspension lines are then laid back and forth across the pack transversely and within the pocket 17, the bight portions of the lines being held by the usual keepers. The portions of the lines adjacent the spirit of the canopy are then carried across the partition 14 into the pocket 16 and the canopy then folded back and forth in the pockets 14 and 15 over the partition 13. In packing the canopy a greater portion is distributed in the longitudinal pockets 27 and at the sides of the pack than at the intervening portion of the pack, thus causing the pack to take the back conforming shape illustrated in Figure 4.

The flaps are then closed in the usual manner and secured by the cone fasteners and rip cord, and in closing the flaps the canopy and suspension lines are of course compressed as is usual in packing.

Finally the elastic cords 9 and 10 are drawn over the front of the pack and secured to the flaps in the usual manner, passing over the side bars of the frame and being located in the grooves 11 and 12.

Thus part of the packed canopy will be located in the pocket 15 and, passing over the partition 13 which is reenforced and maintained in form by the top cross bar of the frame in any of the forms of Figures 6, 7 or 8, the other portion will be located in the other transverse pocket 16 while the lines will be located in the pocket 17, a portion, however, passing over the reenforced partition 14, and of course at the sides of the pack portions 45 of the canopy in both of the pockets 15 and 16 will be located in the longitudinal pockets 27. The result of this packing in this form of pack will be that the canopy and, indeed, the suspension lines will be prevented from shifting either longitudinally or transversely of the pack.

An additional positioning action will take place for the elastic cords 9 and 10 are of course drawn tightly around the pack and they will coact with the cross bars of the frame and with the partitions to maintain the canopy and suspension lines in position because they resist the stretching action which is necessary if the portion of the canopy that is in one pocket is to shift to the other pocket. And they thus exert pressure on the portions of the canopy that overlie the partitions.

It will be noted that in this pack the portion that projects rearwardly toward the back of the user is entirely free of any portion of the stiffening frame for the frame is located substantially at the front of the pack to an extent at least equal to the depth of the grooves 11 and 12. The result is that, while the pack possesses all of the virtues of a frame stiffened pack it also possesses all of the advantages of a soft pack and it possesses none of the disadvantages of either.

Moreover, because of the ability of the frame to flex and articulate the pack will adapt itself to the movements of the user without impeding

his movements and it will return to its normal form.

When permitted to do so by the movements of the user, this tendency to return to its normal form will be augmented by the resiliency that is lent to the pack by the compression of the canopy in packing.

It is of course to be understood that changes in many details of form and material may be made without departing from the scope or spirit of the claimed invention.

What is claimed is:

1. In a parachute pack having a back and a front, stiffening means for the pack remote from the back of the pack toward the front of the pack, said means including cross bars extending transversely of the pack, an end section hinged to one cross bar, and independent end pieces hinged to the other cross bar and secured to the sides of the pack.

2. In a parachute pack having a back and a front, stiffening means for the pack located remote from the back of the pack toward the front of the pack, said means including cross

bars extending transversely of the pack and independent side bars secured to said cross bars and secured at the sides of the pack.

3. In a parachute pack having a back and a front, stiffening means for the pack located remote from the back of the pack toward the front of the pack, said means including cross bars extending transversely of the pack and independent side bars attached to said cross bars and secured at the sides of the pack.
